US00D979060S

(12) **United States Design Patent** (10) **Patent No.:** **US D979,060 S**
Raphael et al. (45) **Date of Patent:** **** Feb. 21, 2023**

- (54) **LIP IMPLANT**
(71) Applicant: **SurgiSil, L.L.P.**, Plano, TX (US)
(72) Inventors: **Peter Raphael**, Plano, TX (US); **Scott Harris**, Dallas, TX (US)
(73) Assignee: **SurgiSil, L.L.P.**, Plano, TX (US)
(**) Term: **14 Years**
(21) Appl. No.: **29/491,550**
(22) Filed: **May 22, 2014**

Related U.S. Application Data

- (63) Continuation of application No. 13/174,914, filed on Jul. 1, 2011, now abandoned, which is a continuation of application No. 11/929,267, filed on Oct. 30, 2007, now Pat. No. 7,993,409, which is a continuation of application No. 10/792,984, filed on Mar. 4, 2004, now Pat. No. 7,344,566, which is a continuation-in-part of application No. 10/384,229, filed on Mar. 7, 2003, now Pat. No. 7,008,455.
